MORTAR

Joseph Raymond Jasse, Paris, France, assignor to
 Etablissements Edgar Brandt, Paris, France, a
 French company

Application May 24, 1947, Serial No. 750,254
 In France July 1, 1946

6 Claims. (Cl. 89—1)

1

The present invention relates to a mortar or bomb-thrower adapted to be muzzle loaded. Such mortars are most often provided with a stationary striker which projects from the end of the gun-barrel and is intended to produce the ignition of the propelling cartridge arranged at the rear of the projectile, as soon as said projectile, by the force of gravity, impinges on said striker.

However, for various reasons, it may be an advantage for it to be possible in certain cases to operate the striker by hand. It may happen, for example, that the cartridge misfires; this accident may be caused, either by the fact that the cap is faulty, or because the projectile is braked as it falls into the gun-barrel and only impinges on the striker with insufficient force to produce the ignition of the cartridge; this may occur if the firing angle is small or if the gun-barrel is clogged. If there is no means for enabling the shot to be fired when the percussion has not operated, recourse has to be had to extracting the projectile from the gun-barrel, which may necessitate first of all removing its fuze inside the barrel. It will be understood that this operation, which is delicate, wastes precious time when the enemy is at hand.

This problem may be solved by using a mortar provided with a manually operated firing device and provided with a means for temporarily placing the point of the striker out of reach of the cartridge of the projectile.

Mortars are already known in which a removable finger is interposed between the projectile and the stationary striker, an accessory firing device making it possible to fire the shot at will. Bomb-throwers are also known which comprise a controlled percussion mechanism, but which does not permit of automatic percussion. The combination, in a single device, of automatic percussion and controlled percussion would require a fairly complicated mechanism, the various elements of which would have to be separately mounted in the breech of the mortar; in the event of failure of this mechanism, the mortar itself would be out of action, which would be a serious drawback for a firearm which plays such an important part.

The present invention is intended to avoid these drawbacks and has for its object a mortar of the type having, in its breech, a percussion device which is adapted either to be locked in a projecting position for effecting automatic percussion, or to be made movable for effecting percussion which is controlled by the action of an

2

appropriate control mechanism, said mortar being remarkable in particular in that the mechanism for controlling said percussion device is arranged in an independent case housed in a rear extension of the breech.

This particular arrangement of the controlling mechanism mounted in an independent case has the main advantage of enabling, at any instant, in case of failure, said case with its mechanism to be replaced quickly by a spare case.

According to another characteristic of the invention the independent case is located in a housing which, as it has to be readily accessible, is wide open for this purpose on the outer side in a radial direction relatively to the axis of the gun, in such a manner that the independent case can be removed and replaced by another case, without its being necessary to alter the laying of the gun.

20 In a particular embodiment of a device according to the invention, the mechanism for controlling the percussion is contained in the independent case, whereas the percussion device, constituted for instance by a striker and a rear thrust element connected by a hook to said striker, is located in an axial housing provided in the breech body.

25 The fact of dividing the percussion device into two separate elements has the advantage of considerably simplifying the construction of the device. As the striker comprises a mechanism which operates axially, it is preferably located in a cylindrical housing arranged in the axis of the gun-barrel, and it is quite naturally positioned in the thickness of the breech body.

30 The case for controlling the percussion, on the contrary, comprises members which, to enable them to be controlled from the outside, are only arranged at right angles.

35 40 The control mechanism contained in the percussion case comprises a device which effects the change of the striker from controlled percussion to automatic percussion and vice-versa, and a control device for the controlled percussion.

45 Other advantages and peculiarities of the invention will become apparent from the ensuing description.

50 In the accompanying drawing, which is given solely by way of a constructional example,

Fig. 1 shows, in axial section and in a horizontal position, the breech of a mortar provided with a striker and a percussion case arranged according to the invention, the assembly being in 55 the inoperative position.

Fig. 2 is a vertical section of the percussion case alone, along the line II—II of Fig. 1.

Fig. 3 is a plan view of the percussion case alone.

Referring to said drawing, 1 is the gun-barrel of a mortar adapted to be loaded through the muzzle; 2 is the breech body; 3 the breech head of spherical shape, adapted to engage in the recess of a base plate not shown in the drawing; 4 is the tang of the breech connecting the head 3 to the body 2. The breech body 2 is provided with a longitudinal hole 6 adapted to receive the percussion device; said hole opens respectively in the tube 1 and in a housing 8 menaged in the tang 4. Said housing which is of rectangular parallelepipedic shape opens on the lateral face of the tang. In said housing is located a removable case 7 which is shown separately on Figs. 2 and 3. Said case 7 is constituted in fact by a block (see Figs. 2 and 3) provided with a shoulder 50 which engages a rebate 51 of the housing 8. Said block comprises two cavities 52 and 53 in communication through a longitudinal hole 54 (Fig. 1).

The percussion device, which is movable in the longitudinal hole 6 comprises a striker 9 which is axially movable in a stationary frame 10, and which is urged by a spring 11, through the intermediary of a bush 12, towards a rear position in which its head 13 rests against a seat 14 provided in the frame 10; said frame 10 is screwed to the end of a sleeve-shaped case 15 in which slides behind the striker a bolt member 16 provided, on the one hand, at its front end with a transversal hook 16a disposed with a little gap before the rear head 9b of the striker and, on the other hand at its rear end with a buffer knob 17 ending in the form of a head 17b. A projection 18 of the sleeve 15 outwardly limits the travel of the bolt member 16; a spring 19 urges said bolt member towards the projection 18.

The striker 9 is provided, at its front end, with a point 9a which, in the percussion position, projects outside the frusto-conical housing 20 provided in a cap 21 which is screwed in the breech body 2 and holds the striker in its housing. At its rear end, the striker 9 is provided with a buffer knob 9b.

In Fig. 1, the detonator 9 is shown in the inoperative position, ready to be actuated by the control mechanism carried by the case or block 7. The change from this position to the automatic percussion position and vice-versa is effected by a device adapted to be actuated by means of a control knob 22. Said knob 22 is secured, by means of a screw 23, to an internally screw-threaded sleeve 24 in which is screwed a rod 25 which is provided at its lower part with a slot 25a and at its upper part with a head 25b sliding in the knob 22 and adapted to project outside said knob.

A bent lever 26, mounted on a spindle 27, in the cavity 52 of case 7, engages with one of its arms 26a in the slot 25a of the rod 25, against the bottom of which it is kept pressed by a spring 28, whereas with two other arms 26b, arranged parallel in the shape of a fork straddling the buffer knob 17 before the rear head 17b in a direction at right angles with respect to the longitudinal axis of the striker, it is adapted to exert a pressure against the bolt member 16.

By screwing the knob 22 on the rod 25, as shown by the arrow A (Fig. 3), said rod is caused to move axially downwards; by means of the bent lever 26 the movement is transmitted in the axial

direction to the member 16; said member compresses the spring 19, comes into contact in its turn with the buffer knob 9b and, continuing its travel, drives back the striker 9, against the action of the spring 11, until the instant when the percussion point 9a bears firmly against the tapered bottom of the housing 20. By screwing the knob 22 right home, the striker 9 is thus locked in the automatic percussion position, the end of its point 9a permanently projecting inside the gun-barrel.

The reverse operation is effected by unscrewing the control knob 22 in the direction shown by the arrow C (Fig. 3); by the action of the springs 11 and 19, the striker 9 and the bolt member 16 respectively return to their original positions, as soon as the bent lever 26 ceases to exert a pressure on the member 16, which occurs when, owing to the unscrewing of the knob 22, the rod 25 itself returns to its upper position.

The position assumed by the striker, i. e. either the automatic percussion position, or the controlled percussion position, is continually shown on the outside by the head 25b of the rod 25 which acts as a pointer; when said head projects outside the control knob 22, the striker is in the controlled percussion position, whereas when it is completely retracted, the striker is locked in the automatic percussion position.

The control device for controlling the percussion, which is entirely enclosed in the removable case 7, comprises a hammer 29 movable in the longitudinal hole 54 of said case. Said hammer, of hollow cylindrical shape, is so arranged as to enable it to strike axially the buffer knob 17 of the bolt member 16 when said hammer 29 is subjected to the expansion action of the percussion spring 31 housed in its cylindrical part. Said hammer is prolonged at its front end by a finger 29a which ends in the form of a transversal hook, the plane rear face of which is at right angles with respect to the longitudinal axis of the percussion device and is disposed with some gap before the rear head 17b of the bolt member 16 between the two arms 26b of the lever 26.

The spring 31 is enclosed between the front end of the hammer 29 and a cylindrical pusher 32 adapted to slide inside said hammer by the action of a cocking finger 33 fixed on transverse spindle 34 which is itself rotarily actuated by a cocking lever 35 (Fig. 3).

A cylindrical sear 36, which is located in the rear cavity 53 of the case 7 and continually urged by a spring 37 towards its engaged position, is so arranged as to engage with its nose 38 in an opening 39 provided in the hammer and to lock said hammer while, by the action of the cocking lever, the pusher 32 compresses the percussion spring 31.

A disc 40, which is preferably secured to the finger 33, is fixed on the spindle 34 and is provided with a trip nose 41 arranged so as to impinge, at the end of its travel, on an abutment 42 secured to the sear 36 and is adapted to lift same slightly, thereby disengaging the escape-movement pawl 38; said pawl releases the hammer 29 which suddenly drives back the member 16 against the knob 9b of the striker and produces the percussion.

The device is automatically returned to the starting position by the cocking finger 33 which is so arranged as to be, in the axial direction, continually in contact, except during the compression period of the percussion spring 31, at a point 43 located between its axis of rotation

and its bearing point on the pusher 33, with a part 44 of the hammer forming an abutment. Owing to the difference of leverage between the axis of rotation of the finger 33 and these two points of contact, the couple acting, by the action of the spring 31, on the finger 33 is stronger than that acting, in the opposite direction and by the action of this same spring, on the hammer 29; said hammer is thus driven back by the cocking finger which is itself returned to the original position by the pusher 32, up to the point where the sear 36 engages again and locks the controlled percussion mechanism.

In this return movement, the hammer 29 carries with it by means of its hook finger 29a, the buffer knob 17 and the bolt member 16, said bolt member in its turn, carrying with it the striker 9 by means of its hook finger 16a. This arrangement has the advantage of its always being certain, when the cocking lever 35 is returned to its starting position, that the striker is not in its automatic percussion position in which it could otherwise have been locked by seizing for example, the springs 11 and 19 not having in that case sufficient force to retract it of their own accord, whereas the head 25b projecting from the control knob 22 would nevertheless continue to show the controlled percussion position, which might involve the gunners in serious accidents.

As can be seen in Fig. 1, the cocking finger has, at the point 43 where it is in contact with the abutment 44 of the hammer, a domed shape such that the perpendicular which is common to this shape and to the abutment of the hammer at their point of contact constantly extends in a direction which is as nearly as possible that of the axis of the hammer, the force applied by the finger to the hammer being thus directed in a direction parallel to said axis.

The cocking device can be locked in the inoperative position by means of a bolt 46 adapted to engage in a groove 47 of the trip disc 40, said bolt being secured to a spindle 48 which is controlled from the outside by means of a knob 49. When said knob 49 is in the direction of arrow A (Fig. 3) the cocking device is unlocked. On the contrary, when said knob is in the direction of arrow S, the cocking device is locked in its inoperative position and the firearm is thus completely safe.

It is obvious that the invention has only been illustrated and described by way of example and that, without exceeding its scope, various modifications could be made therein.

Having now described my invention what I claim as new and desire to secure by Letters Patent is:

1. In a muzzle-loading mortar a gun-barrel and a breech comprising a breech body provided near the front with means for fixing it to the barrel of said mortar and near the rear with an axial extension provided with a cavity which is open towards the outside in a radial direction relatively to the longitudinal axis of the breech, a percussion device adapted to move in said breech body between a front position in which it projects from said body into said barrel in order to enable an automatic percussion of the cartridge to be fired when said cartridge is inserted into said barrel and a rear position in which said percussion device is retracted in said body to adapt said percussion device for controlled percussion of said cartridge, and a removable case housed in said cavity and containing means for moving said percussion device from any of said

positions to the other and a control device for controlling said controlled percussion by means of said percussion device, said means and control device being in contact with said percussion device, only by plane transversal surfaces perpendicular to said longitudinal axis of said breech and said control device comprising a hammer adapted to move axially in said case and to impinge on the rear end of the percussion device when this latter is in its rear position, a percussion spring bearing with one of its ends on said hammer on the opposite side to the percussion device, a pusher bearing against the other end of said spring, a cocking finger enabling said pusher to be moved in the direction of the compression of said spring, a cocking lever acting on said finger, and a sear detent for locking said hammer until the instant when the pressure of said spring is sufficient to produce the percussion.

2. A breech according to claim 1, wherein said hammer is provided with an opening while said sear detent comprises in combination: a sear adapted to move in said case in a direction at right angles to that of the hammer and provided with a pawl adapted to engage in said opening, a spring acting on said sear to cause said pawl to penetrate into said opening, and means provided on said cocking lever for retracting said pawl at the end of the cocking stroke of said pusher and thereby releasing the hammer.

3. A breech according to claim 1, wherein said hammer is provided with an opening while said sear detent comprises in combination: a sear adapted to move in said case in a direction at right angles to that of the hammer and provided with a pawl adapted to engage in said opening, a spring acting on said sear to cause said pawl to penetrate into said opening, a disc provided with a trip nose fixed on the spindle of said cocking lever and an abutment secured to the sear in such a position that at the end of the travel of said lever the sear is moved by said nose against the action of said spring, thereby releasing the hammer.

4. A breech according to claim 1, wherein said cocking finger is in contact with a rear extension of said hammer in a rearward axial direction, at a point located between its axis of rotation and its point of contact with the pusher.

5. A breech according to claim 1, wherein said cocking finger is in contact with a rear extension of said hammer, in a rearward axial direction, at a point located between its axis of rotation and its point of contact with the pusher, said finger having, at the point where it is in contact with said hammer, a domed cross-sectional shape which is fairly nearly circular, so that the perpendicular which is common to this cross-section and to the hammer at their point of contact constantly extends in a direction which is as nearly as possible that of the axis of said hammer.

6. A breech according to claim 1 wherein said percussion device comprises a front striker and a rear thrust element connected by a hook to said striker, said element ending at the rear by a buffer knob provided with a rear head located before said hammer which is provided with a front hook disposed before said rear head, said means for moving said percussion device comprising a lever which ends in the shape of a fork straddling said buffer knob.
